[57] **CLAIM**

The ornamental design for a combination key ring and housing for remote control switch, as shown and described.

DESCRIPTION

FIG. 1 is a perspective view of a combination key ring and housing for remote control switch showing my new design, in accordance with a first embodiment of the present invention, and shown with representative environment control buttons represented by broken lines to indicate that these representative environment structures are not a part of the present invention;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof;

FIG. 8 is a perspective view of a combination key ring and housing for remote control switch showing my new design, in accordance with a second embodiment of the present invention, and shown with representative environment control buttons represented by broken lines to

indicate that these representative environment structures are not a part of the present invention;
FIG. 9 is a front view thereof;
FIG. 10 is a right side view thereof;
FIG. 11 is a left side view thereof;
FIG. 12 is a rear view thereof;
FIG. 13 is a top view thereof; and,
FIG. 14 is a bottom view thereof.
